F. W. SPANGLER

WOVEN WICK

Filed June 30, 1924

INVENTOR.
Frederick W. Spangler
BY *Thomas G. Stewart*

ATTORNEY.

UNITED STATES PATENT OFFICE.

FREDERICK W. SPANGLER, OF CHICAGO, ILLINOIS, ASSIGNOR TO THE MANTLE LAMP COMPANY OF AMERICA, OF CHICAGO, ILLINOIS, A CORPORATION.

WOVEN WICK.

Application filed June 30, 1924. Serial No. 723,295.

The invention relates to the construction of wicks which are, preferably of the woven variety, and it concerns the arrangements of the constituent elements thereof.

5 The novelty disclosed is the variation in the spacing of the weft cords, which hold the warp cords and constitute the wick. At the upper extremity or burning end of the wick, the weft cords are spaced relatively close together, to produce a compact wick which will not fray out during its use, while at the lower and bifurcated end of the wick, which is immersed in oil, the weft spacing is approximately twice as great as at the 10 upper end, making the lower end of the wick materially looser in weave. This construction facilitates and cheapens the manufacture and cost of making wicks due to the increased production and decrease in amount 15 of weft cords used.

Furthermore, a wick woven according to this design has an increased oil-capillarity due to the looseness of the weave throughout the major portion of its length. This 20 design makes it possible to give the upper end of the wick a stiff weave, so that the burning end will hold its shape properly, and at the same time the lower end, which is immersed in the oil, is woven looser in order to increase 25 the capillarity.

The invention will be understood if reference be made to the accompanying drawing, in which—

30 Figure 1 is a view showing the wick in elevation, and

Figure 2 is a sectional view taken on the line 2—2, Figure 1.

1 is the entire wick, while 2 and 3 are, respectively, the upper portion and the lower 35 loosely-woven portion. The warp threads 4 and the weft threads 5 are made of cotton

or any suitable substance, and the weft threads below the point marked 6, or other point of predetermined altitude, are spaced sufficiently to produce the desired looseness, 45 the quantity of oil which may be drawn by capillary action to the flame in a given time, being somewhat dependent upon the openness of the submerged part of the wick. It has been found that satisfactory results may 50 be attained if the lower weft threads are arranged twice as far apart as the upper weft threads.

The wick is tubular and may be made on a loom which is capable of producing a tubular wick, the variation of weft cord spacing being attained by varying the take-up mechanism of the loom in a manner well known to workers in the textile art. 55

A wick made as herein described, will not 60 fray out at its upper end which will be relatively stiff, even though the submerged portion is so loose as to be incapable of retaining a definite tubular form. Also, there is 65 the advantage of cheap production due to the lessening of the quantity of yarn required to produce a wick, as well as to a decrease in the time absorbed in weaving. The wick is cleft at the lower end, so that it 70 may straddle the vane which unites the concentric tubes of a central-draft burner.

Having thus described my invention, what I claim is:

A cylindrical woven wick including uniformly spaced warp threads, and weft 75 threads, said weft threads in the lower part of the wick being more widely spaced than the weft threads in the upper part of the wick.

In testimony whereof I affix my signature.

FREDERICK W. SPANGLER.
